UNITED STATES PATENT OFFICE.

KASBER KAZARIAN, OF PROVIDENCE, RHODE ISLAND.

BOBBIN HOLDER FOR BRAIDING MACHINES.

Application filed October 31, 1925. Serial No. 66,090.

To all whom it may concern:

Be it known that I, KASBER KAZARIAN, a citizen of Armenia, residing at Providence, in the county of Providence and State of 5 Rhode Island, have invented a new and useful Improvement in Bobbin Holders for Braiding Machines, of which the following is a specification.

My invention has reference to an improvement 10 in braiding machines and more particularly to an improvement in bobbin holders for the bobbin carriers of braiding machines.

The object of my invention is to improve 15 the construction of a bobbin holder for braiding machines, whereby the operation of feeding the thread from the bobbin is greatly facilitated.

A further object of my invention is to 20 simplify the construction of such a bobbin holder thereby reducing the cost of manufacturing to a minimum.

My invention consists in the peculiar and 25 novel construction of a bobbin holder for braiding machines, said bobbin holder having details of construction as will be more fully set forth hereinafter and claimed.

Figure 1 is a side view of a conventional 30 form of a bobbin carrier for braiding machines, said bobbin carrier being provided with my improved bobbin holder.

Figure 2 is a top plan view of my improved bobbin holder.

Figure 3 is a bottom plan view of the 35 bobbin holder, and

Figure 4 is a vertical view of the bobbin holder looking in the direction of the arrow *a*, Figure 2.

In the drawing 5 indicates a bobbin carrier 40 having the usual vertical spindle 6, bobbin 7, vertical tension weight support 8, tension weight 9 and connecting web 10, which extends centrally and vertically from the enlarged base of the spindle 6 to the tension weight support 8. The bobbin 7 has the usual teeth 11, 11 on its lower end and the thread 12 is drawn from the bobbin through a side eye 13 in the tension weight support 8, then down through and under the tension weight 9 and then up through a top eye 14, as shown in Figure 1. The thread 12 then goes to the point of braiding the braid.

My improved bobbin holder 15 is constructed to have a central spindle hole 16

which is wider than the spindle 6 to allow a tilting movement of the bobbin holder. A flat top 17 is formed on the bobbin holder on which the teeth 11, 11 of the bobbin 7 rest. On the flat top 17 is formed a high 60 vertically projecting tooth 18 and two comparatively low teeth 19, 19, which engage the teeth 11, 11 on the bobbin 7. A hook 20 is formed on the bobbin holder opposite the high tooth 18 and two legs 21, 21 are 65 formed on the underside of the bobbin holder adjacent to and on a central line with the hook 20, the legs 21, 21, straddling the web 10, to prevent the bobbin holder from turning on the spindle 6, and a semi-circular 70 collar 24 is formed on the flat face 17, all formed integral, as shown in Figures 2, 3 and 4. A wire 22 is secured at its lower end to the hook 20 and has an upper end 75 bent at right angles around the tension weight support 8, as shown in Figure 1.

When in use with the braiding machine in operation the thread 12 is drawn in the direction of the arrow *b*, thereby raising the tension weight 9, the weight of which gives 80 the required tension on the thread. When the top of the tension weight 9 reaches the upper bent end 23 of the wire 22, it raises the wire and tilts the bobbin holder 15 into the position shown in broken lines in Figure 85 1, thereby freeing the teeth 18 and 19, 19, on the holder 15 from the teeth 11, 11, on the bobbin 7 and releasing the bobbin. A predetermined amount of thread 12 is now 90 released and the tension weight 9 again assumes its lowest position, as shown in full lines in Figure 1, as the thread is being drawn to the point of braiding, not shown. By this construction of the bobbin holder 15, when the high tooth 18 on the bobbin 95 holder 15 is released from a bobbin tooth 11, the low teeth 19, 19, on the bobbin holder 15 hold slightly on the bobbin teeth 11, 11, until they are released from the bobbin teeth 11, 11, thereby giving a more uniform feed 100 of the thread, then has heretofore been done.

Having thus described my invention I claim as new:

1. A braiding machine bobbin holder having a high tooth adapted to engage the teeth 105 on a braiding machine bobbin and a low tooth adapted to engage the bobbin teeth, for the purpose as described.

2. A braiding machine bobbin holder having a high tooth adapted to engage the teeth 110

of a braiding machine bobbin and two low teeth adapted to engage the bobbin teeth, for the purpose as described.

3. A braiding machine bobbin holder having teeth adapted to engage the teeth on a braiding machine bobbin and legs adapted to straddle a web on a braiding machine bobbin carrier, for the purpose as described.

4. A braiding machine bobbin holder having a high tooth adapted to engage the teeth on a braiding machine bobbin, a low tooth adapted to engage the bobbin teeth and legs adapted to straddle a web on a braiding machine bobbin carrier, for the purpose as described.

5. A braiding machine bobbin holder having a high tooth adapted to engage the teeth

on a braiding machine bobbin, two low teeth adapted to engage the bobbin teeth, legs adapted to straddle a web on a braiding machine bobbin carrier and a hook on the holder, all formed integral, for the purpose as described.

6. A braiding machine bobbin holder having a flat top, a high tooth adapted to engage the bobbin teeth, two low teeth adapted to engage the bobbin teeth, legs adapted to straddle a web on a braiding machine bobbin carrier and a hook on the holder, all formed integral, for the purpose as described.

In testimony whereof, I have signed my name to this specification.

KASBER KAZARIAN.
